George Picot of Hoboken N. J.
Assign to

The Rubber Clothing Company of N. Y. City
Letters Patent No. 24493. Dated Oct 9. 1866
Design for a child's comb.

Illustration referred to in these Letters Patent and making a part of the same.

To all whom it may concern,

Be it known that I, George Picot, of Hoboken in the County of Hudson, and State of New Jersey have invented or produced a new and original Design for Ornamenting children's comb; and I hereby declare the following to be a full, clear and exact description of the same, reference being had to the accompanying drawing.

The Design there shown is what I call the "chain border".

It consists of a series of loops of the desired size and shape, springing one from the other and forming a continuous band or border. The loops are made from one piece of wire which is bent and twisted so as to form loops of desired size which are pressed and flattened so as to form a smooth and continuous band. They are formed so near each other that their contiguous edges will touch, or lap one upon the other, in succession from right to left, or vice versa, the general effect of the Design however being the same.

This band or border of loops is placed around the upper part of the face of the comb in a line parallel with its top edge and is held to the comb by pins, or pins which project out therefrom. Upon these projecting ends, are secured, or mounted, beads, which as well as the wire border may be of any color to suit the taste or fancy of the wearer.

Having described my invention what I claim and desire to secure by Letters Patent is

The Design for ornamenting children's comb, as herein shown and described.

In testimony whereof I have signed my name to this Specification before two subscribing witnesses.

Witnessed,

André Anderson Jr.

James Gontier Jr.
